UNITED STATES PATENT OFFICE.

OSCAR F. HAMMAR, OF LEECHBURG, PENNSYLVANIA.

CIGARETTE-ROLLER.

No. 823,217.

Specification of Letters Patent.

Patented June 12, 1906.

Application filed November 25, 1905. Serial No. 289,094.

To all whom it may concern:

Be it known that I, OSCAR F. HAMMAR, a citizen of the United States, residing at Leechburg, in the county of Armstrong and State of Pennsylvania, have invented new and useful Improvements in Cigarette-Rollers, of which the following is a specification.

The object of my invention is to provide a new and improved cigarette-roller; and to this end my invention consists of a cigarette-roller, in the novel features of construction, and in the combination of parts, all as hereinafter fully described and claimed.

In the accompanying drawings, which illustrate application of my invention, Figure 1 is a side elevational view of an apparatus constructed in accordance with my invention with the lid or cover removed. Fig. 2 is a vertical sectional view showing the rollers pushed back and the device ready to receive the tobacco; Fig. 3, a broken plan view; Fig. 4, a vertical sectional view showing the rollers moved inwardly and the tobacco in position; Figs. 5 and 6, detail views of rocker tension mechanism; Fig. 7, a vertical sectional view showing the parts inclosed by a lid or cover. Fig. 8 is a part side elevational view and a part-sectional view of a modified form, showing a lid or cover; and Fig. 9, a vertical sectional view of the form of Fig. 8.

Referring to the drawings, the body portion 1 of my cigarette-roller is preferably made of sheet metal of any convenient shape and has formed integral therewith end portions 2. Each of the end portions is formed with two slots 3, which slots terminate in downwardly-projecting loops 4.

Extending from end to end of the body portion are two rollers 5. These rollers each have a journal 6, which latter are located in the curved slots 3 and are arranged to be freely moved therein from the outer ends of the slots to the looped portions 4. For convenience in moving said rollers 5 from their separated positions, as shown by Fig. 2, to the looped portions 4, as shown by Fig. 4, the journals 6 are extended outwardly for a slight distance beyond the ends 2.

Formed integral with the body 1 and at each side thereof I employ a ledge or stop 7. The function of these ledges 7 is to limit the movements of a rocker tension device and to coöperate with the tension device to change the tension on the traveling apron, as herein-after more fully described. This tension device forms an important and characteristic

feature of the present invention, and by its use I am enabled to make a firm and well-formed cigarette from various kinds of tobacco. The tension device, as illustrated 60 and as preferred, consists of a rocker comprising bars or rods 8 and end pieces 9. In practice the rocker tension device is formed as an integral structure; but it is evident that it may be constructed of separate parts suitably connected.

10 designates the apron or ribbon which is provided with handles 11 for drawing the apron or ribbon through the apparatus. Handles 11 also serve as stops during the operation of forming the cigarette. As clearly shown by the drawings, ribbon 10 is located under the rods 8 of the tension device and extends upwardly and around the two rollers 5. The looped portions 4 are so spaced as to 75 cause the rollers 5 to come quite close together when their journals are in said loops. Sufficient space, however, is left to permit the ribbon to pass between the rollers and to insert a paper wrapper 14. The tension device 80 is centrally journaled within the body on pins 13, which latter in the forms illustrated project inwardly from the ends 2.

In forming a cigarette the parts are first arranged in the position shown by Fig. 2— 85 that is, with the guide-rollers 5 spread apart and in the outer ends of the two slots 3—and the apron depressed within the body to form a loop to receive the tobacco. After the tobacco is placed on the depressed portion of 90 the apron the guide-rollers are moved by hand from the outer ends of the slots 3 to the looped portions 4, or into the position shown by Fig. 4. While in this position the apron or ribbon is pulled in either direction, causing 95 the tobacco to be rolled into shape to receive the wrapper 14. The paper wrapper 14 is inserted into the space 12 and between the rollers 5, as particularly shown by Fig. 4. Then by pulling the apron the wrapper is drawn 100 into the roller and wound around the tobacco-filler, thus completing the cigarette. The tension upon the apron or ribbon is varied, as desired, by the tension device. By the employment of my tension means I am enabled 105 to use various kinds of tobacco in making cigarettes and to so regulate the tension of the ribbon to produce uniform and well-rolled cigarettes. The tension upon the apron is varied as required by moving the bars of the 110 tension device toward and away from the ledges 7, and the said bars are so moved by a

slight change in the direction of pull upon the ribbon. Thus in Fig. 4 I have represented the ribbon or apron as being pulled in an upwardly direction. A pull in this direction 5 raises one bar of the tension device and causes the other bar to be lowered and to bear upon and pinch the apron between said bar and one of the ledges 7. It will be noted that the tension upon the apron may be still further 10 increased by changing the angle of pull on the ribbon or by lifting the raised bar of the tension device to a still higher plane than that shown by Fig. 4. The tension of course may be lessened by slightly raising the bar from 15 the ledge.

15 designates a cover or lid for the roller, and in the form of Fig. 8 I have shown the cover hinged to an end of the body, and for this purpose I extend the pin 13 through the 20 end, as clearly shown by Fig. 8. The dotted line in Fig. 9 indicates the cover swung free of the upper part of the body.

What I claim is—

1. A cigarette-roller comprising a casing 25 provided with an apron contacting surface, a rocking tension device, an apron arranged between the contacting surface and the tension device, said tension device operated by a pull upon the apron, substantially as set 30 forth.

2. A cigarette-roller comprising a casing, a rocking tension device comprising end pieces connected by cross-rods, an apron arranged between a portion of the casing and a cross- 35 rod, said tension device operated by a pull upon the apron, substantially as set forth.

3. A cigarette-roller comprising a body portion, a traveling apron, guide-rollers, a rocking tension device, said apron arranged 40 to pass under the tension device and over the guide-rollers, substantially as set forth.

4. A cigarette-roller comprising a casing having end pieces formed with slots or openings, a traveling apron, movable guide-rollers arranged to be moved in the slots or openings, 45 a tension device, said apron arranged to be passed under the tension device and over the guide-rollers, substantially as set forth.

5. A cigarette-roller comprising a casing formed with longitudinal ledges, a traveling 50 apron, guide-rollers, a tension device, said apron arranged to pass between the tension device and the ledges and over the guide-rollers, substantially as set forth.

6. A cigarette-roller comprising a casing 55 having longitudinal ledges or supports and end pieces formed with slots, a traveling apron, movable guide-rollers arranged to be moved in the slots, a tension device, said apron arranged between the tension device 60 and the ledges or supports and over the guide-rollers, substantially as set forth.

7. A cigarette-roller comprising a casing having end pieces formed with slots terminating in a downward looped portion constituting 65 roller-guides, rollers arranged to be moved in said guides, a traveling apron, and a rocking tension device, substantially as set forth.

8. A cigarette-roller comprising a body portion formed of a single piece of metal having 70 end pieces formed with slots terminating in a looped portion, a traveling apron, guide-rollers arranged to be moved in the slotted end pieces, a rocking-tension device and a removable lid or cover, substantially as set 75 forth.

In testimony whereof I affix my signature in presence of two subscribing witnesses.

OSCAR F. HAMMAR.
